CLAIM

I claim the ornamental design for an IV line organizer, as shown and described.

DESCRIPTION

FIG. 1 is a perspective view of an IV line organizer, showing our new design.

FIG. 2 is a front view of the claimed design.

FIG. 3 is a rear view of the claimed design.

FIG. 4 is a left side view of the claimed design.

FIG. 5 is a right side view of the claimed design.

FIG. 6 is a top view of the claimed design; and,

FIG. 7 is a bottom view of the claimed design.

The broken lines appearing in FIG. 6 and FIG. 7 are environmental matter and form no part of the claimed design.
